UNITED STATES PATENT OFFICE.

JAMES J. HENNESSY, OF NEW YORK, N. Y.

LUBRICATOR FOR LOCOMOTIVE JOURNALS.

1,412,739.

Specification of Letters Patent. Patented Apr. 11, 1922.

Application filed January 17, 1920. Serial No. 352,098.

To all whom it may concern:

Be it known that I, JAMES J. HENNESSY, a citizen of the United States, residing at New York city, New York, have invented a 5 certain new and useful Improvement in Lubricators for Locomotive Journals, of which the following is a full, clear, and exact description, such as will enable others skilled in the art to which it appertains to make and 10 use the same, reference being had to the accompanying drawings, forming part of this specification.

My invention has relation to improvements in locomotive journal lubricators, and 15 consists in the novel details of construction more fully set forth in the specification and pointed out in the claims.

The invention relates particularly to lead truck and driving journal lubricators, and 20 has for its object the provision of a lubricator as directly driven from the journal by means of cams or equivalent devices.

A further object of the invention is to provide a duplex pump so constructed as to 25 be directly driven by the cams dispensing with springs for the return movement of the plungers and further simplifying the construction so as to render the lubricator readily applied in a roundhouse.

30 Further and other objects are better apparent from a detailed description of the invention in connection with the accompanying drawings, in which,—

Figure 1 is a vertical section lengthwise 35 of the journal showing my lubricating device secured thereto.

Figure 2 is a vertical section through the journal box and cellar.

Figure 3 is a vertical section on the zig-zag line 3—3 of Figure 1.

Figure 4 is a horizontal section on the zigzag line 4—4 of Figure 1.

Figure 5 is a horizontal section on the line 5—5 of Figure 1.

45 Figure 6 is a face view of the cams and wedge rings assembled.

Figure 7 is a sectional detail on the line 7—7 of Figure 6.

Figure 8 is a face view of the tightening 50 ring which holds the cams in place.

Figure 9 is a sectional detail on the line 9—9 of Figure 8.

Referring to the drawings, 1 is a lead or driving journal box provided with the usual

brass 2 and cellar 3, and 4 represents the journal traversing said journal box. Positioned within the cellar 3 and beneath the journal 4 is a plate 5 between which and the journal is the waste W whereby the journal is provided with lubrication. The waste W is kept in contact with the journal 4 by means of the coiled spring 6 which bears lightly against the bottom of the plate 5, thus forcing said plate toward the journal.

An oil reservoir R is secured to the cellar of the journal by means of bolts b, or can be integral, and within this reservoir are located the pumps consisting of plungers 7—7 operating within cylinders 8—8. The cylinders 8 are cast integrally with the pump reservoir, and beneath said cylinders is a port 9, said port 9 communicating with a second port 10, the latter port being located between the cellar 3 and pump cylinders. The lower edges of the cylinders 8 form a valve seat 75 against which ball valves 11—11 are adapted to seat. The check valves are maintained in seated position by means of springs 12—12. The passage 10 is closed at its upper end by a block 13, and is provided at 80 its lower end with a ball check valve 14, said ball 14 being maintained in its seated position by means of a spring 15 which bears against the perforated stop 16 placed in the passageway 10 a sufficient distance away 85 from the ball 14 to permit said ball to unseat. The upper portions of the cylinders 8 are connected by a web 17, said web being slotted to accommodate a lever 18 pivoted on a pin 19, the ends of said lever entering 90 slots 20—20 in the plungers. Cams 21 are mounted on the journal 4 above the plungers, said cams being formed in two pieces so as to be readily applied to the journal. The cams 21 are provided with cam faces a near 95 their outer edges, and with beveled faces 22 opposite the cam faces, which beveled faces are adapted to bear against wedge rings 23, each of which is formed in three pieces in order that they may be readily 100 placed in position (see Figure 6). The cams are provided with screw threads opposite their inclined faces to receive retaining rings 24, the latter also being made in two sections to permit ready application. Each 105 of said sections is provided with lugs 25 whereby said sections are secured together by means of bolts 26. From the foregoing, it

is readily apparent that the cams may be readily mounted on the journal without removing the journal.

It is understood that when the engine is running there is a certain amount of lateral movement of the journal, and in order to accommodate this movement the cam faces *a* of the cams are made wide enough so that said faces will remain in engagement with the plungers 7 notwithstanding such lateral movement.

The engaging walls of the cellar 3 and reservoir R are provided with a port 29, said port communicating with the cellar 15 below the plate 5 and with the chamber 10 of the reservoir and a port 30 communicating with the cellar above the plate 5 and the reservoir. The cylinders 8 are provided with intake ports 31 through which the oil 20 enters the cylinders from the reservoir.

The reservoir R is provided with a cover 27 secured to said reservoir by means of bolts 28 so that the entire pump mechanism is enclosed.

It will be understood that a sufficient amount of oil is placed in the reservoir. When the engine is running the journal 4 with the cams 21 will rapidly rotate, said cams alternately depressing plungers 7, one 30 of which will be raised by the lever 18 when the other is depressed, which plungers in their downward movement will force the oil that has entered the cylinders through the ports 31 past the ball valves 11 and 14, then 35 up through the passage 10 and port 29 into the cellar 3 below the plate 5. The oil will find its way from here into the waste compartment, thus saturating the waste, and any surplus oil will, under the pump action, be 40 forced outwardly through the port 30 back into the oil reservoir. It is understood that this action continues so long as the journal 4 is

rotating, thus insuring a circulation of oil from the reservoir into the cellar and through the waste back into the reservoir. 45

It is obvious that the invention is susceptible of modifications falling within the spirit thereof and of which I wish to avail myself.

I claim:

1. In a journal lubricator, pump cylinders, slotted plungers in said cylinders, a pivoted lever having spherical ends in said slots for connecting said plungers, and means for alternately depressing said connected plungers. 55
2. In a journal lubricator, a pump, parallel plungers in said pump, a slot in each of said plungers, a lever pivoted between said plungers to the pump body with its arms extending respectively into said slots, 60 and means for alternately thrusting said plungers in one direction.
3. In combination with an engine journal, pumps adjacent thereto, cams on the journal, said cams being provided with 65 bevel faces for actuating the pumps, wedge rings enveloping the journal and engaging the cams, and confining rings on the outer ends of the cams.
4. In combination with an engine journal, an oil reservoir, pump cylinders within the reservoir and communicating therewith, plungers in the cylinders, cams on the journal, said cams having bevel faces for actuating the pumps, wedge rings enveloping the 75 journal and engaging the cams, confining rings on the outer ends of the cams and a lever pivotally mounted between the plungers, the ends of said lever engaging said plungers. 80

In testimony whereof I hereunto affix my signature this 12th day of January, 1920.

JAMES J. HENNESSY.
